FIG.2

FIG.3

FIGURE 1 is a perspective view of a plastic ribbon showing my new design;

FIGURE 2 is a cross-sectional view taken on the line 2—2 of FIGURE 1; and

FIGURE 3 is a transverse cross-sectional view taken on the lines 3—3 of FIGURE 1.

The characteristic feature of my design resides in the combination on a ribbon of spaced apart linear side edges and between them concave and convex blisters standing out in relief alternately, all as shown.

We claim:

The ornamental design for a plastic ribbon, as shown and described.
